UNITED STATES PATENT OFFICE.

MARIA E. ALLEN, OF BROOKLYN, NEW YORK.

DIAPER.

SPECIFICATION forming part of Letters Patent No. 355,368, dated January 4, 1887.

Application filed March 20, 1886. Serial No. 195,976. (No model.)

To all whom it may concern:

Be it known that I, MARIA E. ALLEN, of the city of Brooklyn, county of Kings, and State of New York, have invented a new and 5 Improved Diaper or Infant's Breech-Cloth, of which the following specification is a full, clear, and exact description.

This invention relates to infants' breech-cloths; and it consists in a combination of various materials for that purpose, as herein-after described.

In the accompanying drawings, Figure I represents a diaper as applied to an infant. Fig. II shows a top view of the diaper in an 15 unfolded state. Fig. III represents a section of part of a diaper on an enlarged scale.

This diaper consists of a layer of cotton wadding, *a*, above a sheet of paper, *b*, the latter being covered by a fine gauze material. 20 The different materials are stitched together near the edges *s*. (See Fig. II.) To give free circulation of air the paper *b* is perforated.

This diaper, which is of the usual triangu-

lar shape, is applied on the infant in the usual manner by passing one corner between the 25 limbs upward and the two other corners of the diaper around the body until they meet the first corner, where all the corners are secured together. The usual diaper at present generally used is then put outside this improved diaper in the usual manner.

This improved diaper is for the purpose that when it becomes soiled it may be thrown away and replaced by a clean one. Thus the outside diaper is kept clean, and may be used 35 for some length of time before requiring to be washed.

I claim as my invention—

As a new article of manufacture, a ventilating-diaper consisting of a combination of 40 cotton wadding, perforated paper, and gauze, substantially as specified.

MARIA E. ALLEN.
